UNITED STATES PATENT OFFICE.

JOHN M. MARIS, OF CHICAGO, ILLINOIS.

ROLLED-STEEL BOLSTER FOR CARS.

SPECIFICATION forming part of Letters Patent No. 602,910, dated April 26, 1898.

Application filed December 9, 1897. Serial No. 661,252. (No model.)

To all whom it may concern:

Be it known that I, JOHN M. MARIS, a citizen of the United States, residing in Chicago, in the county of Cook and State of Illinois, have 5 invented a new and useful Improvement in Rolled-Steel Bolsters for Cars, of which the following is a specification.

My invention relates to steel or metal bolsters for cars formed of rolled beams having 10 an upper and lower flange and an intermediate web and which are given a truss shape by inclining or bending one or both of the flanges at an angle to the other, a wedge or gore shaped piece being cut out of the web at each 15 side of the middle to enable the upper and lower flanges of the beam to be bent or inclined to the required truss shape.

By my invention instead of cutting out a rectangular area of the web at each end of 20 each beam where the flanges are required to be parallel to each other I simply slit the web and offset it, so that one edge of the slit web will pass the other, the offset portions forming shoulders to abut together, and I then secure the lapped portions of the web together 25 by rivets or other suitable devices inserted through the lapped portions of the web. A triangular or gore-shaped area is cut out of the web at each end back of the slit portion and extending back as far toward the middle of the beam as it is desired to have the upper and lower flanges incline toward each other.

In the accompanying drawings, forming a 30 part of this specification, Figure 1 is a side elevation of a car-bolster embodying my invention. Fig. 2 is a plan view. Fig. 3 is an enlarged side elevation. Fig. 4 is a cross-section through one of the flange-beams of the 35 bolster on the line 4-4 of Fig. 3. Fig. 5 shows in side elevation the blank for forming the truss-shaped beams of the bolster, showing the same after the web is slit and the triangular area cut out of the same, but before 40 the upper and lower flanges are bent or inclined toward each other to give the beam its required truss shape.

In the drawings I have illustrated my invention as constructed with the particular 45 style or shape of rolled-steel beams commonly known as "deck-beams" and in which the upper flange is flat and the lower one round; but

it will be understood by those skilled in the art that in practicing my invention ordinary I-beams or channel-beams may be used or 55 other shaped beams having upper and lower flanges and an intermediate web.

In the drawings, A represents the bolster, the same being composed of two flanged beams B B, placed side by side and secured together 60 by suitable castings C C' and each having an upper flange b, a lower flange b', and an intermediate web b².

The upper and lower flanges b b' are bent or inclined toward each other, one or both, as 65 may be preferred, from the middle portion of the bolster toward each end, as indicated in the drawings, (the upper and lower flanges being, however, parallel to each other for a short distance, preferably about one foot, at 70 each extreme end,) to give the beam the required truss shape. This is done by forming a slit b³ in the web at each end extending toward the middle, preferably about twelve inches, or as far as the parallel portion of the 75 upper and lower flanges in the finished beam, and by cutting out a triangular or gore-shaped piece b⁴ from the web at each side of the middle of the beam and extending as far as the upper and lower flanges, one or both, are inclined. On each side of the slit b³ the web is offset, forming shoulders b⁵ and portions b⁶, that lap past each other when the upper and lower flanges of the beam are bent or inclined toward each other to give it the truss shape. 85

After the upper and lower flanges, one or both, are thus bent or inclined toward each other the lapped portions b⁶ b⁶ of the slit web are secured together by rivets D or other suitable devices inserted through holes drilled 90 in the lapped portions of the web, thus forming and rigidly securing together the upper and lower severed members of the flanged beam. In the bolster A two of these truss-shaped rolled-steel flange-beams are secured 95 together side by side by the center plate C and other castings C', one preferably at each end.

The slit and shouldered portion of the web may be extended back any length desired; but I prefer to only extend the slit and shoulders back the length of the parallel portion of the beam at each end and not along the inclined portion of the flange or flanges 100

of the beam, as in practical manufacture it is more convenient to make the offsets and shoulders in the web parallel to the slit than it would be to form such offset and shoulders also at an angle to the slit to give the necessary taper or truss shape to the beam.

In the drawings at Fig. 1 I have shown my invention as applied both to an upper or body bolster and to a lower or truck bolster, both, however, being substantially the same in construction, excepting that in the body-bolster the upper flange of the beams is straight throughout, the lower flange alone being inclined or bent, and in the lower or truck bolster both the upper and lower flanges are preferably bent or inclined.

I claim—

1. In a car-bolster, a rolled-steel truss-shaped beam having upper and lower flanges and an intermediate web, the web being longitudinally slit at each end of the beam, and provided with shoulders and offset portions lapping past each other, and rivets or other devices inserted through the lapped portions of said web for securing the same together, the upper and lower flanges of the beam being bent or inclined, one or both, at an angle to each other, the two slotted edges of the web abutting against the two shoulders or offsets at the lapped portions of the slotted web, substantially as specified.
2. In a car-bolster, a rolled-steel truss-shaped beam having upper and lower flanges and an intermediate web, the web being longitudinally slit at each end of the beam, and provided with shoulders and offset portions lapping past each other, and rivets or other devices inserted through the lapped portions of said web for securing the same together,

the upper and lower flanges of the beam being bent or inclined, one or both, at an angle to each other, and said web having also a triangular or gore-shaped piece cut out on each side of the middle of the beam to enable said upper and lower flanges to be bent or inclined 45° toward each other, and the slotted and shouldered portion of the web lapped, substantially as specified.

3. The combination in a car-bolster of a pair of truss-shaped rolled-steel beams placed side by side and secured together, and each having upper and lower flanges and an intermediate web, the web having a longitudinal slit at each end and provided with abutting shoulders and offset portions lapping past each other and rivets securing the lapped portions together, the upper and lower flanges of each beam being bent or inclined, one or both, at an angle to each other, substantially as specified.

4. The combination in a car-bolster of a pair of truss-shaped rolled-steel beams placed side by side and secured together, and each having upper and lower flanges and an intermediate web, the web having a longitudinal slit at each end and provided with abutting shoulders and offset portions lapping past each other and rivets securing the latter portions together, the upper and lower flanges of each beam being bent or inclined, one or both, at an angle to each other, and said web having also a triangular or gore-shaped piece cut out at each side of the middle, substantially as specified.

JOHN M. MARIS.
